NECKTIE RACK

Cyril Kruger, New York, N. Y.

Application July 20, 1950, Serial No. 174,845

9 Claims. (Cl. 211—96)

1

This invention relates to new and useful improvements in necktie racks; and, more particularly, the aim is to provide a novel and valuable necktie rack of the kind having a large number of necktie supports spaced along a pair of centrally disposed parallel bars and also of the kind wherein there is included a plurality of necktie supports each arranged so that it provides separately engageable means for each of two neckties, with such a support preferably being a link member made of a length of bent wire and with one of said means always being a terminal subdivision of said wire member.

With the necktie rack or hanger of the present invention of the kind wherein one of said bars is to be immovably secured to a wall, and wherein the two bars are so connected that the bar other than the said fixed one is endwisely movable relative to said fixed bar thereby in one position of the movable bar to arrange all the said link members substantially perpendicular to the wall and in another position of the movable bar to arrange all said link members substantially parallel with the wall, a feature of the present invention is that an improved assemblage of parts is provided which is characterized by the advantages that, on the one hand, all said terminal subdivisions are offset from the same side of the rack when the latter is expanded to cause its said link members to become arranged substantially perpendicular to the wall, and, at the same time, some of said terminal subdivisions are above the two bars and all others of said terminal subdivisions are below the two bars, while the movable bar is always spaced further away from the wall than the fixed bar.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top plan view of a now approved embodiment of the rack or hanger of the invention, in expanded condition; with hidden parts of one of a multiplicity of like bent wire link members indicated in broken lines.

Fig. 2 shows said rack or hanger front elevationally, in expanded condition as in Fig. 1; with hidden parts of one of the link members of the kind last referred to, and also with the hidden parts of one of the two other like bent wire link members, indicated in broken lines.

2

Fig. 3 is a view corresponding to the left end portion of Fig. 2, showing the hanger in collapsed condition.

Fig. 4 is a view corresponding to the right end portion of Fig. 1, showing the hanger in collapsed condition.

Fig. 5 is an end elevation, looking toward the right in Fig. 2.

Fig. 6 is a perspective view of one of said multiplicity of bent wire link members.

Fig. 7 is a vertical section taken on the line 7—7 of Fig. 2.

Fig. 8 is a perspective view of one of said pair of bent wire link members.

Fig. 9 is a vertical section taken on the line 9—9 of Fig. 2.

Referring now to the drawings more in detail, a pair of parallel bars are shown, the upper and lower ones of which are designated 15 and 16, respectively.

The two bars 15 and 16 are pivotally interconnected at uniform spacings along their lengths by a multiplicity of bent wire link members 17, and, near the opposite ends of the rack or hanger, by two bent wire link members 18. As will be noted from Figs. 1 and 2, each of the two end link members 18, at the inner end of a terminal subdivision 19 thereof, is spaced from the next adjacent one of the several link members 17, at the inner end of a terminal subdivision 20 thereof, to the same extent as are thus spaced apart the various members 17.

In the present case, enough of the link members 17 are shown present to provide, in combination with the two link members 18, both of which latter are exactly alike, a total of fifteen of said terminal subdivisions 19 and 20. These terminal subdivisions 19 and 20, each constituting a hanger means for being individually and separately engaged by a different one of a plurality of neckties, will below be called the hooks 19 and 20.

Each of the link members 17, all exactly alike, is shaped and arranged so that its hook 19 is always above both bars 15 and 16, and each link member 18, both as just above stated exactly alike, is shaped and arranged so that its hook 20 is always above both bars 15 and 16; while each of the link members 17 is shaped and arranged so that its terminal subdivision 21, or hook 21 as the same will below be called, is always below both bars 15 and 16. That is to say, when the parts are disposed as in Figs. 1 and 2, there are twenty-eight of the said hooks and consequently twenty-eight different neckties may be indi-

ividually hung from the rack with each necktie draped over a different one of the hooks. There are two less of the hooks 21 than the total of hooks 19 and 20, as will be noted; this because in each of the link members 18, as shown best in Figs. 8 and 9 in the case of one of them, has its lower portion so formed as to incorporate, instead of a part corresponding to a hook 21 of a link member 17, a special hook formation with a vertically upturned hook bill 22.

The lower bar 16, near each of its opposite ends, is upwardly vertically recessed as at 23 (Figs. 2 and 9), for the pivotal reception in each such recess of the hook bill 22 at the lower portion of a link member 18. Said lower bar 16, also, is vertically apertured at thirteen uniformly spaced points along its length, for pivotally receiving in each such aperture a lower vertically extending portion of a link member 17; one such aperture being designated 24 in Figs. 2 and 7 and said lower vertically extending portion of a link member 17 being designated 25 in Figs. 2, 6 and 7. The spacing between each two apertures 24 is the same as between a recess 23 and the next adjacent aperture 24.

The upper bar 15 is vertically apertured at each of fifteen uniformly spaced points along its length; with each of two of such apertures (26, Figs. 2 and 9) for pivotally receiving the upper part of a main vertically extending portion (27, Figs. 8 and 9) of a link member 18; and with each of thirteen of such apertures (28, Figs. 2 and 7) for pivotally receiving the upper vertically extending portion (29, Figs. 6 and 7) of a link member 17. The uniform spacing between said apertures along the bar 15 is the same as between the apertures 24 along the bar 16.

Considering the bottom portion (30, Figs. 2, 8 and 9) of each link member 18 as a swing arm or crank element at the opposite ends of the main structure provided by the bars 15 and 16, an equivalent swing arm or crank element (31, Figs. 1 through 7) is included in each link member 17, with the last-named swing arm or crank element located midway along the length of a link member 17.

Due to the placements as already described of the recesses 23 and of the apertures 24 and 26 on the main structure provided by the bars 15 and 16, and due to the fact that the working lengths of the bottom crank-like portions 30 of the link members 18 are the same as the working lengths of the crank-like portions 31 of the link members 17, when the bar 15 is endwise moved relative to the bar 16, with the latter fixed for horizontal extension against a wall or the like in any suitable way as by means of screws or the like sent through holes 32 in the bar 16 near its opposite ends, endwise movement of the upper bar 15, which is shown as slightly shorter than the bar 16, may be effected, in one direction or the other, in one case to arrange the parts as in Figs. 1 and 2 to expand the rack, and in the other case to arrange the parts as in Figs. 3 and 4 to collapse the rack, but always to maintain the bar 15 further from the wall than the bar 16.

When moving the upper bar 15 to completely expand the tie rack, the vertically extended portions 27 of the endmost link members 18 strike the front face of the bottom bar 16, see Figs. 5 and 9, when the link members 17 reach a position extended right angularly from the bar 16. Thus, those vertically extended portions 27 in cooperation with the front face of the bottom bar 16 function as stops to limit movement of

the upper bar 15 in a direction to expand the tie rack.

On collapse of the rack, the hooks 19, 20 and 21 are forced in toward parallelism with the wall, and so as to impose holding pressures on the neckties hung on all or various ones of said hooks.

It will be appreciated, therefore, that there has been provided a hanger or rack capable of individually supporting a large number of neckties in a minimum of space, and a hanger or rack characterized by the advantages that, on the one hand, all the individual necktie hooks are arranged to be projected from the same side of the rack when the latter is expanded, and, also, a large plurality of said hooks are always above the upper one of two bars and a large plurality of said hooks are always below the lower one of said two bars. These hooks are all parts either of a link member 17 or of a link member 18, and the two bars 15 and 16 are operatively coupled, securely yet simply, by a swing-arm or crank element incorporated in each of all the link members 17 and 18.

While I have illustrated and described the preferred embodiment of my invention, it is to be understood that I do not limit myself to the precise construction herein disclosed and the right is reserved to all changes and modifications coming within the scope of the invention as defined in the appended claims.

I claim:

1. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of certain of said link members having a terminal subdivision offset in relation to the vertical portion of the link member above the upper bar, and all of said subdivisions constituting an array of necktie supporting hooks swingable to positions substantially perpendicular to the wall in response to endwise movement in a desired direction of the bar other than the one secured to the wall.

2. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of

said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of certain of said link members having a terminal subdivision offset in relation to the vertical portion of the link member above the upper bar, and all of said subdivisions constituting an array of necktie supporting hooks swingable to positions substantially perpendicular to the wall in response to endwise movement in a desired direction of the bar other than the one secured to the wall, certain of said link members having their said crank elements between the two bars.

3. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of certain of said link members having a terminal subdivision offset in relation to the vertical portion of the link member above the upper bar, and all of said subdivisions constituting an array of necktie supporting hooks swingable to positions substantially perpendicular to the wall in response to endwise movement in a desired direction of the bar other than the one secured to the wall, certain of said link members having their said crank elements between the two bars, and certain other of said link members having their said crank elements below the lower bar.

4. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of said link members having a terminal subdivision offset in relation to the vertical

portion of the link member above the upper bar, and certain of said link members having a terminal subdivision offset in relation to the vertical portion of the link member below the lower bar, and all of said subdivisions constituting an array of necktie supporting hooks swingable to positions substantially perpendicular to the wall in response to endwise movement in a desired direction of the bar other than the one secured to the wall.

5. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of a lesser number of said link members having a terminal subdivision offset in relation to the vertical portion of the link member above the upper bar, and each of a greater number of said link members having a terminal subdivision offset in relation to the vertical portion of the link member below the lower bar, and all of said subdivisions constituting an array of necktie supporting hooks swingable to positions substantially perpendicular to the wall in response to endwise movement in a desired direction of the bar other than the one secured to the wall.

6. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of a lesser number of said link members having a terminal subdivision offset in relation to the vertical portion of the link member above the upper bar, and each of a greater number of said link members having a terminal subdivision offset in relation to the vertical portion of the link member above the upper bar and also a terminal subdivision offset

in relation to the vertical portion of the link member below the lower bar, and all of said subdivisions constituting an array of necktie supporting hooks swingable to positions substantially perpendicular to the wall in response to endwise movement in a desired direction of the bar other than the one secured to the wall, said horizontal portions offset in relation to the vertical portion of the link members being so arranged that when said hooks of said greater number of link members are swung to positions substantially perpendicular to the wall the upper ones of the last-named hooks are horizontally staggered relative to the lower ones thereof.

7. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of a lesser number of said link members having a terminal subdivision offset in relation to the vertical portion of the link member above the upper bar, and each of a greater number of said link members having a terminal subdivision offset in relation to the vertical portion of the link member above the upper bar and also a terminal subdivision offset in relation to the vertical portion of the link member below the lower bar, and all of said subdivisions constituting an array of necktie supporting hooks swingable to positions substantially perpendicular to the wall in response to endwise movement in a desired direction of the bar other than the one secured to the wall, each of said greater number of said link members having its two terminal subdivisions in two vertical planes spaced apart a distance substantially equal to the length of said intermediate horizontally offset portion, said two terminal subdivisions being substantially horizontal when one of said bars is secured to a wall as stated.

8. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion for constituting a swing arm or crank element, each of said crank elements having the same working length and being shaped and arranged always to maintain the bar other than the one secured to the wall a further distance from the wall than said bar secured to the wall.

bar, each of said link members having intermediate its ends a horizontal portion offset in relation to its vertical portion constituting a swing arm or crank element, each of said crank elements having the same working length and being shaped and arranged always to maintain the bar other than the one secured to the wall a further distance from the wall than said bar secured to the wall, each of a lesser number of said link members having a terminal subdivision offset in relation to the vertical portion of the link member above the upper bar, and each of a greater number of said link members having a terminal subdivision offset in relation to the vertical portion of the link member above the upper bar and also a terminal subdivision offset in relation to the vertical portion of the link member below the lower bar, and all of said subdivisions constituting an array of necktie supporting hooks swingable to positions substantially perpendicular to the wall in response to endwise movement in a desired direction of the bar other than the one secured to the wall, each of said greater number of said link members having its two terminal subdivisions in two vertical planes spaced apart a distance substantially equal to the length of said intermediate horizontally offset portion, said two terminal subdivisions being substantially horizontal when one of said bars is secured to a wall as stated.

9. A necktie hanger which comprises as its main structure an upper bar and a lower bar parallel to said upper bar, and a plurality of bent wire link members pivotally interconnecting said bars whereby with one of said bars secured immovably to a wall in horizontal placement thereon an endwise movement of the other bar may be effected in either direction, each of said bars having a plurality of vertically extended apertures and each of said link members being vertically extended through one of said apertures in one of the bars and also vertically extended through one of said apertures in the other bar, each of said link members having intermediate its ends a horizontal portion offset in relation to its vertical portion for constituting a swing arm or crank element, each of said crank elements having the same working length and being shaped and arranged always to maintain the bar other than the one secured to the wall a further distance from the wall than said bar secured to the wall.
